UNITED STATES PATENT OFFICE

ROBERT SCHÖBERL, OF BUDAPEST, HUNGARY

CHAIR CONVERTIBLE INTO A BEDSTEAD OR COUCH

Application filed June 23, 1928, Serial No. 287,834, and in Hungary July 28, 1927.

This invention relates to an improved construction of arm-chair convertible into a bedstead or couch.

According to the invention the back-rest 5 is constituted by two juxtaposed frames hingedly connected to one another at their upper edges, the forward one of these frames being hingedly connected at its lower edge to the rear portion of the seat frame or to the 10 arm-rests, and the rear one of said first-mentioned frames being provided on its inner face at its lower end with supporting feet which, in the use of the article as a chair, are each received in a gap between an arm-rest 15 and the seat frame. The said feet-carrying frame is normally supported freely at its lower edge on the rear member of the seat frame and thus holds the back-rest against tilting backwards. In the vicinity of the 20 hinged joint between the two frames constituting the back-rest there is provided on one of said frames an additional pair of feet which are hingedly mounted so as to depend freely and which, when the chair is converted 25 into a bedstead, assume a vertical position under the influence of gravity, forming an additional support for the bedstead. The seat is preferably of wedge form and tapered rearwards to serve as a pillow when the article is used as a bed without necessity for 30 displacement of the seat. The seat frame is formed as a box to accommodate the bedclothes, the seat forming a cover for the box, for which purpose the seat is hinged at its 35 rear edge to the seat frame. The chair structure, which may be of wood or metal, may be upholstered in the usual manner or may be covered with elastic wire fabric to serve as a camp bed.

40 In the accompanying drawing which illustrates a construction according to the invention, assumed to be made of wood, Fig. 1 is a perspective view showing the chair-frame in full lines; the dotted lines representing 45 the positions of the parts when the article is converted into a bedstead. Fig. 2 shows the upper part of one of the frames of the back-rest with auxiliary feet hinged thereto. Fig. 3 shows the upholstered chair in vertical 50 section, indicating in dotted lines the posi-

tions assumed by the parts in the first stage of the conversion of the chair into a bedstead, the seat being indicated in dotted lines in raised position.

Referring to the drawing, 1 and 1' indicate 55 the two frames forming the back-rest and interconnected at their upper edges by hinges 2. The forward frame 1 is adapted to be tilted rearwards on hinges 3 at its lower edge, being hinged to the rear ends of the arm-rests 5, while the rear frame 1' is provided with rigid feet 6 projecting inwardly into gaps between the seat frame 4 and the arm-rests 5 and said frame 1' rests at its lower edge on the rear member of the seat frame 4. 60

To the upper rail of the rear frame 1' of the back-rest auxiliary feet 6' are hinged at 7 so as to hang freely, said feet serving in the use of the article as a bed to support the two frames 1 and 1' in a horizontal plane 70 (as shown in dotted lines in Fig. 1). The seat frame 4, formed as a box 8 to accommodate the bedclothes, is provided with a seat 9 forming a cover for the box, said seat 9 being mounted on hinges 10 at its rear lower edge so that it may be lifted as shown in dotted lines in Fig. 3. The seat 9 is of wedge 75 section, tapering towards the rear, so that in the use of the article as a bed or couch it may serve as a pillow.

80 For the purpose of converting the chair into a bed or couch, the frame 1' of the back-rest is first swung in the direction of the arrow about the hinges 2 until the feet 6 are free. On further movement of the frame 1' rearwardly the other frame 1 is caused to swing on its hinges until both frames 1 and 1' are brought into the plane of the seat frame 4, as shown in dotted lines in Fig. 1, in which 85 position they are supported by the feet 6 and 6' and in conjunction with the seat frame 4 of the chair form a bed couch, the seat 9 remaining in its place and serving as a pillow.

90 The back-rest may also be provided with the usual lateral head supports 1², which as 95 shown in dotted lines in the drawing, are secured to the rear frame 1' of the back-rest and conceal the gaps between the two frames of the back-rest. Also, as shown partly in dotted lines in Fig. 1, the arm-rests 5 are 100

provided with extensions 5' extending on both sides of the back-rest, so that the arm-rests may be upholstered up to the rear face of the back-rest and also the lower side portion of the arm-rests and the gaps between 5 the back-rest and the arm-rests may be covered.

What I claim is:

An arm-chair convertible into a bedstead or couch comprising, in combination, a seat frame, arm-rests at the sides of said seat frame with gaps between said arm-rests and said seat-frame, and a back-rest hinged behind the arm-rests, said back-rest being constituted by a pair of juxtaposed frames 15 hingedly connected at their upper edges, the rearward one of said pair of frames having feet engageable with said gaps.

In testimony whereof I have signed my 20 name to this specification.

ROBERT SCHÖBERL.
